Primary Examiner — Darlington Ly(57) **CLAIM**

The ornamental design for a scooter, as shown and described.

DESCRIPTION

FIG. 1 is a perspective view of a scooter showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the scooter with the control lever separated; and,

FIG. 10 is a perspective view of the scooter in a second state with the saddle installed to the handlebar and the control lever separated.

The broken lines in the drawings are for the purpose of illustrating portions of the scooter that form no part of the claimed design.
